Cecilia E. Thill, Cloquet, Minn.

Application January 14, 1950, Serial No. 7,249

Term of patent 7 years

(Cl. D3—13)

To all whom it may concern:

Be it known that I, Cecilia E. Thill, a citizen of the United States of America, residing at Cloquet, in the county of Carlton and State of Minnesota, have invented a new, original, and ornamental Design for a Hat, of which the following is a specification, reference being had to the accompanying drawing, forming a part thereof:

In the drawing:

Fig. 1 is a side elevational view of a hat showing my new design.

Fig. 2 is a top plan view of Fig. 1.

I claim:

The ornamental design for a hat, substantially as shown.

CECILIA E. THILL.
